UNITED STATES PATENT OFFICE.

RICHARD H. WILSON, OF NEWARK, NEW JERSEY, ASSIGNOR TO WESTERN ELECTRIC COMPANY, INCORPORATED, OF NEW YORK, N. Y., A CORPORATION OF NEW YORK.

ELECTRON DISCHARGE DEVICE.

1,403,932.

Specification of Letters Patent. Patented Jan. 17, 1922.

Application filed July 18, 1919. Serial No. 311,211.

To all whom it may concern:

Be it known that I, RICHARD H. WILSON, a subject of the King of Great Britain, residing at Newark, in the county of Essex, 5 State of New Jersey, have invented certain new and useful Improvements in Electron Discharge Devices, of which the following is a full, clear, concise, and exact description.

- 10 This invention relates to electron discharge devices in which the impulses to be amplified, repeated or rectified are applied to a control electrode such as a grid. It has been found that in devices of this type, 15 a coated filament having been employed, a potential difference which may be called a contact difference in potential actually exists between the grid and the filament when a current is flowing from the filament to the plate. This potential difference assumes different values for different tubes even in the case where precautions are taken to employ as near as possible the same material for the grid and the same sort of 20 alkaline earth oxide coating for the filament. This difference in potential makes it impossible to always use precisely the same circuit arrangement for the vacuum tube if identical results are to be obtained. 25 In any case, however, this difference in potential is such as to cause no serious difference in the operation of the tube, especially if it is to be employed for amplifying large impulses, but in case the tube is 30 to be employed as a detector or amplifier of weak impulses, it is desirable from a manufacturing standpoint that identical circuit arrangements should give identical results.

If the contact difference in potential has a 35 tendency to a positive value, it is found necessary in certain circuits, such as amplifier circuits, to apply a negative potential to the grid in order to make it negative with respect to the filament. This negative value 40 is desirable in order that no current can flow in the grid-filament circuit of a vacuum tube.

The usual method of applying the negative grid potential is to employ either a separate 45 source, such as a dry cell, or to employ a resistance in the filament circuit, the drop in potential across this resistance being supplied to the grid. In both cases the negative potential is applied to the grid irrespective 50 of the value of the contact difference in

potential between grid and cathode, so that although in general it may improve the action of vacuum tubes, in many cases, that is, where the contact difference in potential is a large negative value, it is detrimental. 60

An object of the present invention is to compensate to some extent at least for the variations in this contact difference in potential between grid and cathode.

This is accomplished by supplying to the 65 grid or control electrode a potential derived from the drop across a resistance which is in circuit with the source supplying the space current between the cathode and anode. This resistance is so connected that the grid 70 acquires a negative potential equal to the drop across it. The drop across this resistance is proportional to the space current and consequently is dependent to some extent on the value of the contact difference 75 in potential, since a positive value thereof will increase the space current, which would increase the negative potential of the grid, thereby cutting down the space current; on the other hand, a negative value of the contact difference in potential will decrease the space current which results in a grid potential 80 tending to increase the space current. Hence the arrangement compensates for variations in this contact difference in potential. 85

For further details of the invention reference may be made to the drawing in which the figure represents diagrammatically a circuit embodying the invention. 90

Referring to the figure in detail, the incoming line 1 is adapted to be traversed by impulses to be repeated substantially without distortion, that is without rectification or modulation and after amplification by the 95 electron discharge device 2 to be received by the receiver 9 or other translating device. Or the line 1 may be supplied with modulated carrier waves, in which case the vacuum tube 2 may function as a detector to 100 render the signals audible in the receiver or other device 9.

The tube 2 contains the usual grid 3, cathode 4 and anode 5. The grid circuit, however, in this case includes the resistance 105 6 which as above described serves to supply a negative potential to the grid. The drop in potential across the resistance 6 is produced by the current flowing from the battery 7 which supplies the space current be- 110

2
 tween cathode 4 and anode 5. The current from battery 7 through resistance 6 is maintained substantially constant by the choke coil 8 and the outgoing impulses are led off to the device 9 by a separate circuit which is connected in shunt to the circuit containing the elements 6, 7, 8.

The value of the resistance 6 employed in practice will of course vary with the type 10 of vacuum tube used, that is, with the amount of negative grid potential desired and the normal plate current. Preferably the value of the resistance 6 should be small as compared with the value of the receiver 15 9. For instance the resistance 6 may be 1,000 ohms—the receiver 9 about 20,000 ohms.

What is claimed is:

1. An electron discharge device having 20 grid and anode circuits, a source of space current, an impedance common to said grid and anode circuits, and means for maintaining substantially constant the current through said impedance.
2. An electron discharge device comprising 25 an anode, a cathode and a grid, a source of space current, a resistance, and a plurality of circuits in shunt to said cathode and anode, one of said circuits comprising said

source, said resistance and a choke coil connected in series, and another of said circuits being the outgoing circuit.

3. An electron discharge device having grid and anode circuits, a source of space current, an impedance common to said grid 35 and anode circuits, and a choke coil in series with said source and said impedance.

4. An electron discharge device comprising an anode, a cathode, and a grid, a source of space current, an impedance in circuit 40 with said source, a choke coil in circuit with said source, means for transferring the potential drop across said impedance to said grid, and a circuit for supplying to said grid the impulse to be repeated, the sources 45 of potential above enumerated being the only sources for assigning to the grid a potential different from that of said cathode.

5. An electron discharge device comprising an anode, a cathode, a grid, a source of space current, and means for supplying between said cathode and grid a potential dependent in value upon the current supplied by said source and substantially independent of the value of the outgoing impulse. 55

In witness whereof, I hereunto subscribe my name this 11th day of July A. D. 1919.

RICHARD H. WILSON.
